United States Patent

Des. 242,426
Patented Nov. 23, 1976

242,426

HOLE CUTTING TOOL

Jack L. Twedell, 6749 S. Delaware, Littleton,
Colo. 80120

Filed May 12, 1975, Ser. No. 576,564

Term of patent 14 years

Int. Cl. D8—03

U.S. Cl. D8—59

FIG. 1 is a perspective view looking down and to the right upon the front of a hole cutting tool showing my design;

FIG. 2 is a rear elevation;

FIG. 3 is an end view looking to the right in FIG. 2;

FIG. 4 is a top plan view;

FIG. 5 is a bottom plan view; and,

FIG. 6 is an end view looking to the left in FIG. 2.

I claim:

The ornamental design for a hole cutting tool, as shown.
